DENTAL ARTICULATING PAPER APPLICATOR

Kenneth E. McVey, Paulsen Bldg.,
Spokane, Wash. 99201

Filed Nov. 28, 1969, Ser. No. 20,296

Term of patent 14 years

Int. Cl. D24—03

U.S. Cl. D24—1

FIG. 1 is a perspective view of a dental articulating paper applicator showing my new design;

FIG. 2 is a top plan view thereof;

FIG. 3 is a bottom plan view thereof;

FIG. 4 is a side elevation view thereof;

FIG. 5 is a section taken along line 5—5 in FIG. 4; and

FIG. 6 is a section taken along line 6—6 in FIG. 4. I claim:

The ornamental design for dental articulating paper applicator, as shown.
